DAIRY PRODUCTS CARRYING BOX

Harold Alton Lunan, Gresham, Oreg.

Application May 28, 1956, Serial No. 41,680

Term of patent 7 years

(Cl. D58—12.6)

FIG.1

FIG. 2

FIG.5

Fig. 1 is an end elevational view of a dairy products carrying box showing my new design;

Fig. 2 is a side elevational view thereof;

Fig. 3 is a top plan view thereof;

Fig. 4 is a top plan view thereof, shown in open position; and

Fig. 5 is a side elevational view thereof, shown in open position.

The side and end views not shown are the same as the side and end views shown.

I claim:

The ornamental design for a dairy products carrying box, as shown and described.
